UNITED STATES PATENT OFFICE.

WILLIAM H. LA FOUNTAIN, OF GLENDALE, CALIFORNIA.

ROTARY DUSTING MACHINE.

Application filed November 12, 1925. Serial No. 63,596.

My invention relates to a rotary dusting machine and has for its principal objects, the provision of a relatively simple, practical and economically operated machine 5 that is especially designed for the extraction of dust from carpets, rugs, draperies, clothing, or, in fact any fabric that contains dust; further, to provide a machine of the character referred to that is practically airtight and dust proof, in that all of the dust extracted from the fabric placed in the machine is caught and held in suitable containers within the machine, thus preventing the extracted dust from leaving the machine and circulating in the room or building in which the extractor is located; further, to provide an improved form of rotary drum wherein the dust laden fabric or articles are constantly agitated during the dust extracting operations; further, to provide for the separation of the heavier particles of dust from the lighter particles, and which latter tend to float in the air, and further, to generally improve upon and simplify the construction of the existing forms of dust extracting machines.

With the foregoing and other objects in view, my invention consists in certain novel features of construction and arrangement of parts that will be hereinafter more fully described and claimed and illustrated in the accompanying drawings in which—

Fig. 1 is a side elevational view of a dusting machine embodying the principles of my invention.

Fig. 2 is a front elevational section of the machine.

Fig. 3 is a rear elevational view of the machine and showing the doors of the dust bag compartments open.

Fig. 4 is a vertical longitudinal section taken approximately on the line 4—4 of Fig. 3.

Fig. 5 is an elevational view of the rotary drum and showing the door thereof.

Fig. 6 is an enlarged detail section taken approximately on the line 6—6 of Fig. 4.

Fig. 7 is a detail section showing a modified arrangement of the air inlet from one of the dust bag chambers into the drum chamber of the machine.

Fig. 8 is a vertical section taken through the central portion of a modified form of the rotary drum.

Referring by numerals to the accompany-

ing drawings which illustrate a practical embodiment of my invention, 10 designates a substantially rectangular housing that may be formed of wood, sheet metal, or a combination thereof, and the front wall of said housing is provided with a relatively large opening that is closed by a door 11, the latter being provided with a suitable latch 12.

Arranged within this housing is the rotary drum that receives the fabric to be cleaned, 65 said drum comprising a pair of slatted disc-shaped sides 13 and a circumferential wall that is made up of transversely disposed slats 14, the ends thereof being secured to the edges of the slatted discs 13. This drum 70 is reenforced on its edges by circumferentially disposed bands 15 of metal and extending around the intermediate portions of the slatted circumference are reinforcing members 16 of wire or metal tape. A portion 75 of the slatted circumference of this drum is formed into a door 17 that is mounted on hinges 18 and which is retained in closed position by suitable latches 19.

Arranged on the inner face of the slatted 80 periphery of the drum and disposed 120° apart are transversely disposed ribs 20 that are substantially V-shaped in cross section with their inner ends rounded as designated by 21, and disposed at intermediate points 25 between these ribs 20 and arranged on the inner face of the slatted periphery are ribs 22, the inner ends of which are enlarged and made substantially oval shape in cross section, thereby providing beater heads such 90 as 23.

As the drum is rotated the ribs 20 and members 22, 23, are designed to engage the fabric and carry the same up to the top of the drum, at which point the fabric drops 95 to the bottom of the drum, and this repeated operation very quickly extracts the dust from the fabric.

Projecting from the sides of the slatted drum are axially disposed trunnions 24 that 100 operate in suitable bearings arranged in the side walls of housing 10, and secured to one of these trunnions is a gear wheel 25.

Secured on the side wall directly above the trunnion that carries the gear wheel is 105 a plate 26 from which projects a trunnion 27 and mounted to rotate thereupon is a hub carrying a pinion 28 and a belt wheel 29. Pinion 28 meshes with gear wheel 25 and belt wheel 29 receives a belt 30 that may be 110

driven in any suitable manner, preferably from an electric motor 31 that is arranged on top of the housing 10.

Arranged beneath the rotary drum and 5 extending from a point near the lower portion of door 11 to a point a short distance inwardly from the rear wall of housing 10 is a curved baffle plate 32 that is concentric with the circumferential wall of the drum 10 and which is designed to receive the heavier particles of dust that discharge from the lower portion of the drum while the same is in operation.

Arranged for sliding movement through 15 the lower portion of the rear wall of the housing is a dust receiving drawer 33, the inner end of which occupies a position beneath the rear end of curved plate 32 when said drawer is in its normal position. Thus 20 all dust that may accumulate on the curved baffle plate 32 will gradually be swept into this drawer 33 and which latter may be withdrawn at any time in order to remove the accumulated dust.

25 Arranged against the rear wall of the housing is a secondary housing 34 that constitutes a dust bag closet and it is divided by a centrally arranged vertically disposed partition 35 into two compartments 36 and 30 37. Suitably hinged doors 38 constitute the outer walls of these dust bag chambers 36 and 37.

35 Arranged on top of this dust closet and above chamber 37 is a suction fan 39, the inlet connection 40 thereof being extended through the upper portion of the rear wall of housing 10. The discharge outlet 41 of 40 this suction fan extends downwardly through the top of housing 34 into chamber 37 and connected thereto is the upper end of a dust collecting bag 42 of woven material such as canvas or drilling.

45 Passing through the upper portion of partition 35 is the upper end of a tubular elbow 43 and connected to the end thereof within chamber 36 is the upper end of a dust collecting bag 44 of suitable woven material such as canvas or drilling but preferably of finer mesh than the material from which bag 50 42 is formed.

55 Formed through the upper portion of the rear wall of housing 10 and establishing communication from chamber 36 with the chamber in which the rotary drum operates is a relatively large aperture 45. In some instances it may be found desirable to dispense with the opening 45 and provide a tubular elbow such as 46 that connects the upper portion of chamber 36 with the interior 60 of housing 10 (see Fig. 7).

Suction fan 39 may be driven in any suitable manner but preferably by means of an electric motor 47, as illustrated in Fig. 3.

65 The operation of my improved dust extractor is as follows: The fabric to be dust-

ed is placed in the rotary drum and after door 17 has been securely fastened, motor 31 is started and the engagement of pinion 28 with gear wheel 25 rotates the drum at a predetermined speed, for instance about 20 revolutions per minute.

The drum rotates in the direction indicated by the arrow in Fig. 4 and the dust laden fabric will be repeatedly carried to the upper portion of the drum by the transverse 75 ribs and beaters on the inner face of the periphery thereof and in falling to the bottom of the drum, the dust will be extracted or beaten from the fabric and the heavier particles of dust will pass onto baffle plate 80 32 and from said plate they will be gradually swept into drawer 33. As motor 47 is operated to drive suction fan 39, dust laden air will be drawn from the upper portion of the chamber within housing 10 through connection 40 and this dust laden air will be forced downwardly through outlet 41 into bag 42 and the greater portion of the dust or the relatively larger particles 85 thereof will be caught in this bag while the air carrying only the finer particles of dust will pass through the wall of the bag and be drawn through tubular elbow 43 into the dust bag 44 of finer mesh or weave.

90 This bag effects a separation of the finer particles of dust from the air, the latter practically free of all dust passing through opening 45 to the chamber within housing 10 and after becoming laden with dust, this air will again be drawn through connection 40 into suction fan 39, and by the latter forced into bag 42.

95 Thus a circulation of air is established from the dusting chamber within housing 10 through the dust collecting bags 42 and 44, 100 and as a result, practically all the dust will be caught in said bags and any air that escapes from the machine will be practically free from dust.

105 At the proper time, or whenever desired, the bags 42 and 44 and the drawer 33 may be removed from the machine and the caught and accumulated dust removed from said bags and drawer.

110 In the event that it is found necessary to admit air to the drum chamber within housing 10, small openings such as *a* are formed in the side of the housing adjacent the trunnion for gear wheel 25 and which openings are controlled by sliding cover plates *b* (see 115 Fig. 1).

120 In Fig. 8 I have illustrated a modified form of the rotary beater, and this form comprises side walls such as 50 provided with centrally arranged perforated doors 51 that give access to the interior of the drum and supported on rods or rollers 52 that are seated in the side walls 50, and upon the inner 125 ends of transversely disposed V-shaped supports 53 is a flexible member 54 of ribbed or 130

corrugated rubber or of a heavy fabric. The ends of this section of material are connected to a clamp 55, the latter having a threaded shank 56 that is engaged by a winged nut 57, thereby providing means for taking up the slack in said member 54 and maintaining the same in a taut condition.

Members 53 are arranged between the members 52 and they project inwardly toward the center of the drum and thus the member 54 provides a flexible wall that is made up of a series of substantially triangular pockets that are effective in repeatedly carrying the dust laden fabric to the top 15 of the drum as the latter is rotated.

In this form of duster, the perforated door 51 is provided on its outer face with a marginal band or drum 51^a that functions as a pulley that receives a belt 51^b from a driven 20 pulley 51^c thus providing simple and efficient means for imparting rotary motion to the drum.

Thus it will be seen that I have provided a relatively simple and practical dusting machine that is especially applicable for extracting the dust from carpets, rugs, draperies, clothing and the like and which machine is constructed so that very little, if any 25 dust laden air is permitted to escape into the room or building in which the machine is located.

It will be readily understood that minor

changes in the size, form and construction of the various parts of my improved dusting machine may be made and substituted 35 for those herein shown and described, without departing from the spirit of the invention, the scope of which is set forth in the appended claim.

I claim as my invention:

In a dusting machine, the combination with a main housing and dusting means arranged for operation therein, of a secondary housing located at the end of the main housing, which secondary housing is divided into 45 two chambers, a suction fan arranged to draw air from the chamber within the main housing and deliver said air to one of the two chambers in the secondary housing, a dust separating bag located in the chamber 50 within the secondary housing to which the suction fan delivers air and connected to said suction fan, a tubular connection between the two chambers in the secondary housing, a dust separating bag connected to 55 said tubular connection and arranged in the other one of the two chambers in said secondary housing and said last mentioned chamber having communication with the interior of the main chamber in which the 60 dusting mechanism is located.

In testimony whereof I affix my signature.

WILLIAM H. LA FOUNTAIN.
